UNITED STATES PATENT OFFICE.

GUSTAVUS BESS, OF SCAPPOOSE, OREGON.

AEROPLANE.

Original application filed July 8, 1921, Serial No. 483,226. Divided and this application filed August 30, 1922. Serial No. 585,176.

To all whom it may concern:

Be it known that I, GUSTAVUS BESS, a citizen of the Republic of Poland, residing at Scappoose, in the county of Columbia 5 and State of Oregon, have invented certain new and useful Improvements in an Aeroplane, of which the following is a specification.

The present invention relates to an aeroplane having for its principal object to provide an improved plane structure of flat and curved sustaining wings, and the subject matter of this application has been divided from my co-pending application, bearing 15 Ser. #483,226 filed July 8, 1921.

In the drawings:

Figure 1 is a view of the aeroplane in side elevation,

Figure 2 is a front elevation thereof, and 20 Figure 3 is a top plan thereof.

The invention comprises an aeroplane body or boat 1 of long narrow construction and tapering toward the rear end as illustrated. At the front end is mounted a single blade propeller 2 which drives the machine with the aid of lifting plane supporting the boat on each side and adjacent the propeller end. These embodying a central plane or wing 3 arched longitudinally and 25 disposed to extend lengthwise of the boat from which it is spaced by sustaining brace rods 4. Projecting laterally from the central plane 3 on opposite sides are supporting bi-planes having respectively, arched forward 30 portions 5 and 5' and straight or flat rear portions 6 and 6'. The portions of each plane respectively constitute front cambered wings and flat parachute or rear wings integrally connected as illustrated at 7 and 7' 35 and disposed on the same straight line as the arch of the front wings, rising above rear wings as noted in Fig. 1. Central wing 3 is arched more than the side wings and extends above the latter being provided with 40 front and rear fins 8 and 9 of suitable formation; the length of the central wing corresponding to the width of the side plane connected thereto. The straight wing on each side plane is provided with a notch or 45 cut out 10 and its outer edge and adjacent the rear outer corner of the preceding

curved wing, this arch constitutes an air passage between the members of each side plane and enlarging the lifting powers of the wings. Projecting outwardly from the boat of the machine adjacent the bottom, are wings 11 and 11' supported by rods 12 and 12' from the upper wings 5 and 5' and curved braces 13 extending downwardly from the flat or parachute wings. The 60 lower wings are cambered more than the upper wings and are of greater width, the rear portions thereof extending across the cut out of the upper parachute wings as shown to advantage in Fig. 3. At the outer 65 rear corner of each end an elongated opening 14 is formed. These openings vary in size, those of the parachute wings being larger than those of the front upper wings. Similar openings are provided in the empennage which comprises a vertical element 15 and horizontal wings 16, the openings 70 17 of the wings being elongated, while openings 18 of the rudder are circular.

The foregoing description and accompanying drawings have reference to what might be considered to be the approved or preferred form of my invention. I desire it to be understood, however, that I may make such changes in the construction, combination and arrangement of parts as may be found expedient and which fall within the scope of the appended claims.

Having thus fully described my invention what I claim is:

1. An aeroplane including a central wing arched longitudinally, a cambered wing projecting laterally from each side of the central wing, a straight wing projecting laterally of the central wing and behind each cambered wing, each straight wing being relatively disposed on the same straight lines with the arch of the cambered wings extending above the plane of the straight wings, and a cambered wing below each first 95 mentioned cambered wing and in spaced relation thereto.

2. An aeroplane comprising a central wing, side planes projecting laterally from each side of the central wing, and respectively having a cambered forward wing and a straight flat rear wing, each straight wing

having a notch or cut out at the outer corner adjacent the arched wings, and a cambered wing located beneath each cambered wing of the side plane and in vertically spaced relation thereto, said lower cambered wings projecting across the cut outs of the straight wings, said side and lower wings having rear outer corners provided with elongated openings extending parallel with the sides thereof. 10

In testimony whereof I affix my signature in presence of two witnesses.

GUSTAVUS BESS.
